UNITED STATES PATENT OFFICE.

EUGENE MOREHOUSE, OF PROVIDENCE, RHODE ISLAND, ASSIGNOR TO B. A. BALLOU & CO., INC., OF PROVIDENCE, RHODE ISLAND, A CORPORATION OF RHODE ISLAND.

SAFETY CATCH.

Application filed January 12, 1926. Serial No. 80,724.

This invention relates to an improved safety catch for pin stems for use on jewelry and the like; and has for its object to provide a safety catch of this character having 5 a body portion with a hook-shaped end to receive the pointed end of a pin stem, a keeper member for closing the hook being pivotally mounted in this body member to slide back and forth through a slot in the 10 back of the body, the keeper being provided with resilient side walls for engaging the side walls of the slot through which it slides to frictionally engage these walls and 15 yieldingly retain the keeper in adjusted position.

A further object of this invention is a provision of laterally-projecting protuberances on these resilient side walls of the keeper which are positioned to frictionally engage 20 the inner surface of the body wall between which it slides whereby when the keeper is moved forwardly to close the hook the protuberances are caused to engage the forward edges of the body to releasably retain the 25 keeper in its closed position.

With these and other objects in view, the invention consists of certain novel features of construction, as will be more fully described, and particularly pointed out in the 30 appended claims.

In the accompanying drawings:

Figure 1 is a side elevation showing my improved safety catch as mounted to receive the pointed end of a pin stem, both being 35 supported on a common base.

Figure 2 is a plan view of a blank as cut and formed from sheet stock from which the body of the catch is formed.

Figure 3 is a central sectional side elevation showing the top of the body portion as bent into hook form and the wings at the lower end thereof as being folded to extend forwardly and remain in spaced relation.

Figure 4 is a view of the back of the body portion of the catch as bent into the form illustrated in Figure 3.

Figure 5 is a section on line 5—5 of Figure 3, showing the forwardly bent wing portions in the inner surface of which are formed recesses to receive and pivotally support the keeper member.

Figure 6 is a rear view of the keeper member as blanked from sheet stock.

Figure 7 is a sectional view on line 7—7 of Figure 6, showing the pivotal trunnions

and the engaging protuberances both as raised from the face of the stock.

Figure 8 is a bottom view showing the blank as having been folded back upon itself, the side walls at the middle portion 60 thereof being spaced apart to frictionally and yieldingly engage the walls of the body portion.

Figure 9 is a side elevation showing the keeper as mounted in the body portion and 65 swung forward into closed position with the protuberances just beyond the inner edges of the body side walls.

Figure 10 is a sectional elevation illustrating the keeper member as swung back to 70 open position to permit free passage of the pin stem into and out of the hook.

It is found in the construction and operation of safety catches of this character, particularly where they are made of precious 75 metal such as gold, platinum, silver and the like, that the continual working of the keeper member to and from its closed position, wears the same and in time becomes loose and will not stay put when moved to its 80 closed position, which often results in the loss of valuable jewelry which it is designed to securely lock on the person of the wearer. To obviate this difficulty, I have formed the keeper member to swing back and forth 85

through a slot in the body and I have formed this keeper member of sheet stock which is folded upon itself forming double resilient side walls spaced apart at their middle portions where they slide through the body slot, 90

whereby the inherent resiliency in the stock serves to press the side walls of the keeper against the walls of the slot with sufficient force to retain the keeper in any desired 95 adjusted position and the resiliency of the keeper side walls is designed to take up the wear in either the body or the keeper, as fast as it occurs and maintain a substantially constant frictional resistance to the movement of the keeper. Then again, to more 100 surely retain the keeper when in its closed position, I have provided laterally-extending protuberances projecting from its opposite resilient side walls so that when the keeper is moved to closed position these protuberances are caused to spring apart just inside 105

of the inner edges of the body thereby providing additional and effective means for preventing accidental opening of the catch and at the same time the resilient walls per. 110

mit this keeper to be swung back into open position when desired; without presenting excessive resistance to such action; and the following is a detailed description of the present embodiment of my invention and showing one construction of safety catch by which these advantageous results may be accomplished:—

With reference to the drawings, 10 designates the body portion of a safety catch which is preferably formed of relatively heavy sheet stock, the upper portion of the body being bent over into fixed hook shape as at 11 and the lower portion of the body 15 is provided with a pair of wing members 12 which are folded forwardly to remain in spaced relation, as best illustrated in Figure 5, and each of these wings is provided on its inner face with a recess 13, which recesses 20 are for the reception of the pivot trunnions of the keeper 9. The forward folding of these wing portions provides an extended base 15 by which the catch may be soldered or otherwise secured to a brooch, bar pin or 25 other base 16, as shown in Figure 1. The rear of this body portion is slotted longitudinally as at 14 through which this keeper member, presently described, is designed to swing back and forth.

30 My improved form of keeper member is preferably cut from relatively thin sheet stock which is formed sufficiently hard to be somewhat resilient and this stock is preferably cut from a blank into the form best 35 illustrated in Figure 6. This blank is preferably folded on its center line to form opposite side walls 17, as best illustrated in Figure 8, which side walls at their middle portions are normally spaced slightly apart 40 as at 19 with their forward edges 18 meeting. These forward edge portions are provided with a pair of laterally-extending integral trunnions 20 forced outwardly from the stock to fit into corresponding recesses 13 formed 45 in the inner surfaces of the side walls of the wings, the rear portion of this keeper extends through the slot 14 of the body and projects upwardly to provide an operating handle 21 and portions of the spaced apart 50 resilient side walls adjacent their middle portions are forced outwardly to provide laterally-extending protuberances 22 having rounding outer engaging surfaces which are formed on this keeper so that when the 55 same is swung forwardly to closed position its forwardly extending nose portion 23 will extend across and close the hook 11 and when in this position these protuberances will be in a position just forward of the 60 edges 24 of the body, whereby the resilient walls of the keeper force these protuberances outwardly and so offer a substantial yet yielding resistance to the opening or backward swinging motion of the keeper and 65 so prevent the keeper from being accidental-

ly opened even if the adjacent fabric should catch upon it, requiring it to be engaged and intentionally operated by action of the wearer, in other words, when it is desired to swing the keeper to open position the 70 handle is engaged and moved back into the position illustrated in Figure 10, thereby causing the resilient side walls to spring slightly inwardly in order to permit the protuberances 22 to pass backwardly in slot 75 14 in the body and the friction of these protuberances against these side walls serves to hold the keeper in any desired adjusted position and when swung forwardly into closed position they spring apart and so 80 offer additional resistance by the spring action of the walls of the keeper, and the inherent spring in the stock of the keeper will thus serve to automatically take up any 85 wear of the parts and so maintain the effective locking action of the catch.

The foregoing description is directed slowly towards the construction illustrated, but I desire it to be understood that I reserve the privilege of resorting to all the 90 mechanical changes to which the device is susceptible, the invention being defined and limited only by the terms of the appended claims.

95 I claim:

1. A safety catch formed with a slotted body portion having a pin tongue receiving hook at its outer end, a keeper member formed of resilient sheet stock folded upon itself and pivoted in said body to slide through the slot therein, said keeper having an operating handle and a hook-closing nose portion, the side walls at the middle portion of the keeper being spaced apart to frictionally engage the side walls of said slot 100 105 with yielding pressure.

2. A safety catch formed with a slotted body portion having a pin tongue receiving hook at one end and having forwardly-folded side wings, a keeper member formed of resilient sheet stock folded upon itself and pivoted in said wings to swing through said body slot, said keeper having an operating handle and a hook-closing nose portion, the 110 115 resilient side walls at the middle portion of the keeper being spaced apart to frictionally engage the side walls of said slot with yielding pressure.

3. A safety catch formed with a slotted body portion having a pin tongue receiving hook at one end and having forwardly-folded side wings, a keeper member formed of resilient sheet stock folded upon itself and pivoted in said side wings to swing through said body slot, said keeper having an operating handle and a hook-closing nose portion, the side walls of the middle portion of the keeper being spaced apart and provided 120 125 with laterally-extending protuberances to frictionally engage the side walls of said slot 130

with yielding pressure to yieldingly retain the keeper in adjusted position.

4. A safety catch formed with a slotted body portion having a pin tongue receiving hook at one end and having forwardly folded spaced side wings, a keeper member formed of resilient sheet stock folded upon itself and pivoted in said side wings to swing through said body slot, said keeper having an operating handle and a hook-closing nose portion, the side walls of the middle portion of the keeper being spaced apart and provided with laterally-extending protuberances to swing forwardly beyond the body walls when closed to releasably retain the keeper in closed position.
5. A safety catch formed with a slotted body portion having a pin tongue receiving

hook at one end, an attaching base at its opposite end, said body also having forwardly folded spaced side wing members, a keeper member formed of resilient stock folded upon itself and pivoted in said side wings to slide through said body slot, said keeper having an operating handle at the back of the body and a hook-closing nose portion at the front thereof, the side walls of the middle portion of said keeper being spaced apart and provided with laterally-extending protuberances to frictionally engage the side walls of said slot and to swing when in closed position forwardly beyond the forwardly-engaging edges of said wings to releasably retain the keeper in closed position.

In testimony whereof I affix my signature.
EUGENE MOREHOUSE.
